UNITED STATES PATENT OFFICE.

JACOB KNAPP, OF NEWARK, NEW JERSEY, ASSIGNOR TO L. S. BRACH, OF NEWARK, NEW JERSEY.

ALCOHOL TORCH.

Application filed February 16, 1921. Serial No. 445,827.

To all whom it may concern:

Be it known that I, JACOB KNAPP, a citizen of the United States, residing in Newark, in the county of Essex and State of New Jersey, have invented certain new and useful Improvements in Alcohol Torches, of which the following is a specification.

This invention has for its main object to provide a portable torch or blow pipe adapted to use liquid fuel, especially alcohol, capable of delivering a blast of flame of intense heat laterally of its body without the use of a pump or other auxiliary means.

Another object is to produce a device that will operate continuously in any position after the initial ignition as long as may be required, at which time the flame is readily quenched.

A further purpose is to provide means whereby the flame may be adjustably controlled when operating.

Still another object is in the provision of means for preventing loss of fuel by evaporation.

These and similar objects are attained by the novel construction, combination and arrangement of parts, hereinafter described and shown in the accompanying drawings forming a material part of this disclosure, and in which:

Figure 1 is a side elevational view showing a torch made in accordance with the invention, part being broken away to disclose the construction.

Figure 2 is a top plan view thereof, indicating in broken lines the jet of flame produced.

Figure 3 is a transverse sectional view taken on line 3—3 of Figure 1.

Stated in general terms the apparatus consists of a flattened oval container for the liquid fuel, the same being conveniently manipulated as a handle and having a nipple at the top with which is engaged a cap.

Secured in the cap is an axial wick tube having a flaring mouth in which the wick terminates. Means adjustable on the cap are provided for spreading the end of the wick and thus controlling the flame.

Another wick, which like the first, extends deeply into the container, passes laterally out of the cap into a burner tube curved to extend over the central wick tube, joining the cap on the opposite side and commun-

cating with its interior through a small orifice. 55

The central portion of the raised tube is flattened and provided with a lateral orifice from which the combustible gas issues when in operation. 60

Referring now more particularly to the drawings, the numeral 10 designates a container shaped preferably like a pocket flask with parallel front and rear walls and curved sides. 65

At the center of the arcuately domed top 11 the material is formed into a coarse pitched screw threaded nipple 12 to which is tight fitted a correspondingly threaded cylindrical cap 14 having near its upper end a fixed transverse plate 15 there being secured in the center of the plate a wick tube 16, its lower end extending into the container while its upper end, above the plate is expanded into a cone 17. 75

The extreme upper end of the cylindrical cap 14 is also screw-threaded externally and engaged thereby is a band or ring 20 having an internal flange 21 provided with a raised serrated margin 22 by which the device can be rotated. 80

A cross bar 23 extends diametrically across, the top of the bar being expanded at its center 24 from the under side of which extends a rigid conical projection 25, in register with the funnel shaped end 17 of the wick tube, which contains a wick 26 extending approximately to the bottom of the container. 85

Another wick 28 rises from the container 90 and passes out of the nipple 12 over its upper edge in a tube 30 fixed to one side of the cap 14 and to which it is fully open.

The tube 30 is bent into a semi-circle, the upper element of the curve blending into 95 a horizontal portion 31, flattened by compressing the wall of the tube laterally, and extended directly over, at some distance above, the center of the tube 16, and provided with a single central lateral orifice 100 32.

The element 31 merges at its opposite end into the reversed semi-circular portion 33 of the burner tube, which like the oppositely curved element 30, is fixed to the cap 14 and communicates with its interior by a small opening 35. 105

The wick 28 extends into the burner tube

30 somewhat past the center of its curvature, while similarly positioned in the symmetrical opposite side 33 is a filling 36 of some fibrous material, as cotton in its natural 5 condition.

In operation, the container having been supplied with liquid fuel by removing the cap or through a filling nozzle (not shown) specially for that purpose, and the wicks 10 entered properly into their respective tubes; sufficient time being allowed for them to become saturated, a spark or flame is applied to the top of the cap, igniting the vapor or gas conducted by the wick 26 into the space 15 above the partition 15, the flame rising through the spaces in the flange 21 and impinging on the burner tube element 31.

The element 31 upon becoming heated receives gases or vapor from the wick 28 and 20 also any that may rise in the cap and thence conducted by the fiber filling 36, the combined gases being superheated by the flame at the top of the cap, which can be controlled by raising or lowering the projection 25 25, thereby loosening or compressing the wick, increasing or diminishing its carrying capacity, and the flame immediately ignites the gases issuing from the orifice 32.

When the flames are quenched and the 30 burner tube cooled the wicks 26 and 28 filling their respective tubes and the filling 36 covering the opening in the cap, effectually preventing loss of fuel material by evaporation or otherwise, it being possible to invert 35 the torch, whether operating or not without leakage or loss.

From the foregoing it will be seen that a 40 neat appearing and convenient torch has been disclosed fully capable of fulfilling its several objects in an effective manner.

While certain preferred embodiments of this device have been shown and described, it will be understood that changes in the form, arrangements, proportions, sizes and 45 details thereof may be made without departing from the scope of the invention as defined in the appended claims.

Having thus described my invention, what 50 I desire to secure by Letters Patent and claim, is:—

1. In a torch, the combination with a container, a wick carried by said container and adjustable means designed to exert pressure on the central portion of the top of the wick, carried by said container for controlling the 55 passage of fluid in said wick.

2. In a torch, the combination with a container, a wick carried by said container, of a burner tube attached to said container, means for conducting fluids from said container to said wick and said burner tube respectively, and means in engagement with and designed to exert pressure on the central portion of the top of said wick for controlling the 60 passage of fluid in said wick.

3. In a torch, the combination with a container, a wick tube carried by said container, of a burner tube having end elements attached to said container at opposite points, the central portion of said burner tube disposed horizontally over said wick tube being contracted and provided with an orifice, and means for conducting fluids from said container to said wick and burner tubes respectively. 70 75

4. In a torch, the combination with a container, a wick tube carried by said container, of a burner tube having end elements attached to said container at opposite points, the central portion of said burner tube disposed horizontally over said wick tube being contracted and provided with an orifice, 80 means for conducting fluids from said container to said wick and burner tubes respectively, and means for controlling the passage 85 of fluid in said wick tube.

5. In a torch, the combination with a container having a threaded nozzle, a cap engaged therewith and a wick tube carried by said cap, of a burner tube having symmetrically curved end elements attached to said cap at opposite points, a central element disposed horizontally over said wick tube, said central element being contracted by flattening the sides one of which contains an 90 orifice, and means for conducting fluids from said container to said wick and burner tubes respectively. 95

6. In a torch, the combination with a container having a threaded nozzle, a cap engaged therewith and a wick tube carried by said cap, of a burner tube having symmetrically curved end elements attached to said cap at opposite points, a central element disposed horizontally over said wick tube, said central element being contracted by flattening the sides one of which contains an orifice, 100 means for conducting fluids from said container to said wick and burner tubes respectively, and means for controlling the 105 passage in said wick tube. 110

7. A torch comprising a container having a threaded nipple, a cap fitted thereover, a wick tube fixed centrally in said cap, a burner tube attached communicatively at its bowed end elements to opposite sides of said cap and extending thereover, said burner tube having a flattened central portion containing a lateral orifice, a wick in said wick tube, another wick in one of the end elements of said burner tube and a fibrous filling in the other bowed element, both of said wicks extending deeply into said container. 115 120

8. A torch comprising a container having a threaded nipple, a cap fitted thereto, a wick carrying tube fixed to extend axially through said cap and having an expanded conical upper end, a perforate cover adjustably engaged on said cap, a projection car- 125 130

ried by said cover adapted to compress a wick within the expanded end of said wick carrying tube, an ovoidal burner tube attached at its ends to opposite sides of said cap, extending in a vertical plane thereabove and containing a single central aperture directed laterally over the cap, and means for conducting liquid fuel from said container to said wick and burner tubes respectively.

9. A torch comprising a flattened elliptical container, a neck formed therewith, an open tubular cap engaging said neck, a transverse partition in said cap, a tube extending through said partition, said tube being expanded conically at its upper end, a perforate cover adjustable on said cap, a conical projection carried by said cover adapted to expand a wick in the conical end

of said tube, an ovoidal shaped burner tube having a central flattened portion containing a lateral orifice disposed in spaced relation directly over the first named tube, the ends of said burner tube being rigidly engaged on opposite sides of said cap, one of the ends being fully open and the other partially closed, a wick in the open end of said burner tube, another wick in the first named tube, said wicks entering said container and fibrous absorbent material disposed in the partially closed end of said burner tube. 20 25 30

This specification signed and witnessed this twenty fourth day of January, 1921.

JACOB KNAPP.
